UNITED STATES PATENT OFFICE.

WILLIAM E. WINE, OF TOLEDO, OHIO.

CAR VENTILATOR.

Application filed March 31, 1924. Serial No. 703,170.

To all whom it may concern:

Be it known that I, WILLIAM E. WINE, a citizen of the United States of America, residing at Toledo, in the county of Lucas and State of Ohio, have invented certain new and useful Improvements in Car Ventilators, of which the following is a specification.

My invention relates to new and useful 10 improvements in ventilators, and especially to ventilators that are adapted for use on freight cars.

One of the objects of the present invention is to construct a ventilator made up of 15 essentially two side pieces, in which are mounted cross bars in the form of angles, between which are located shutters, also formed of angles, the latter being movable so as to open and close the vents between 20 the cross bars.

Still another object of the invention is to provide a ventilator wherein certain lugs hold the cross bars in position while further lugs in the form of tracks guide the movable 25 shutters when operated.

When the term angle is used, it refers generally to metal plates that are in the form of angles, these being readily purchased in the open market, and when arranged for use in the ventilators, simply have to be cut to length, and in one form cut at their both ends to form supporting 30 projections, as will be hereinafter described.

Still another object of the invention is to 35 provide a relatively cheap ventilator wherein the cross bars and the shutters are formed of angles, the movable shutters so arranged that they may, in one form be simply moved inwardly and outwardly to 40 operate the ventilator, or as shown in another form may be moved in a compound manner, that is, upwardly and inwardly, or outwardly and downwardly, depending on whether it is desired to open or close the 45 ventilator.

Still another object of the invention is to 50 provide a ventilator wherein the same may be formed of cross bars and shutters consisting of angular plates, the former supported and the latter supported and guided in the two side pieces, in which in turn are cast projections and tracks, so that the ventilator as a whole will be very

economical to make and also cheap to repair, when necessary.

Still another object of the invention is to 55 form a ventilator with shutters and cross bars wherein the shutters may be quickly and easily operated to an open and closed position.

With these and other objects in view, the 60 invention consists in certain new and novel constructions and combination of parts as will be hereinafter more fully described and pointed out in the claims.

Referring now to the drawings showing 65 a preferred embodiment of my invention,

Fig. 1 is a front view of my improved 70 ventilator as applied to the end of a freight car;

Fig. 2 is a vertical sectional view showing 75 the shutters in their closed position;

Fig. 3 is a similar view showing the 80 shutters in the open position;

Fig. 4 is a detail fragmentary view of the 85 locking dog;

Fig. 4^a is a further fragmentary view of 90 the locking means showing the dog in its other extreme position;

Fig. 5 is a detail fragmentary view of one 95 of the side pieces, as shown in Figs. 2 and 3, the shutters being removed for the sake of clearness;

Fig. 6 is a vertical sectional view of the 100 ventilator showing a slightly modified form, the shutters being in their closed position;

Fig. 7 is a view similar to Fig. 6, with the 105 shutters moved to their open position;

Fig. 8 is a fragmentary perspective of 110 one end of the movable shutters to show how they are supported;

Fig. 9 is a fragmentary sectional detail 115 view taken on line 9—9 of Fig. 6; and

Fig. 10 is a view similar to Fig. 5, but 120 showing the modified side pieces as used in the modified forms shown in Figs. 6 and 7.

Referring now more in detail to the 125 drawings, Figs. 1 to 5 inclusive, there is shown the sheathing 1 of a freight car in which is assembled the ventilator 2 comprising the side pieces 3 and 4, the fixed cross bars 5, the movable shutters 6, the tie bars 7, the operating bar 8, the handle 9 and the dogs 10 pivotally mounted on the 130 bar 8.

Riveted to the tie bars 7 are the metal

straps 11 which in turn are secured by rivets 12 to the plurality of movable shutters 6, as may be clearly seen in Fig. 2.

Referring now more specifically to the 5 cross bars 5 and the shutters 6 (and first to the cross bars 5), it will be seen that they each consist of a plate having the legs 13 and 14, the angle between the legs being ninety degrees, and the depth of each leg 10 being such that it extends nearly across the side pieces 3 and 4, when placed with the apex in the vertical position as shown in Figs. 2 and 3. These plates are readily purchasable in the open market, and of 15 course, may be readily cut to the desired length. They are supported at their opposite ends by the two side pieces 3 and 4, as will be referred to shortly. The movable shutters 6 are formed of similar angles, as 20 heretofore mentioned, and riveted thereto are the straps 11, the shutters being arranged so that their one leg will slide along the one leg of the cross bar when operated, as shown in Figs. 2 and 3.

25 The arrangement of the tracks and lugs is such that when the shutters are pulled downwardly to a closed position, they will tend to slightly wedge against the adjacent legs of the cross bars as may be seen by 30 comparing Figs. 2 and 3.

Referring now specifically to Fig. 5, there is shown the small V-shaped lug or projection 15 and the lug 16, spaced from the lower leg of the projection 15, the spacing 35 being such that it will receive the leg 13 of the cross bar 5. A further guide or track 17 is shown which is substantially rectangular, with the exception that the fourth side is omitted, and it is to be noted that the 40 lower leg 18 of this track 17 is substantially at an angle of 45 degrees to the edge of the side piece, but the upper leg of the V-shaped lug 15 does not parallel the leg 18, it being in a slight angular relation therewith. The object 45 of having this slight angular relationship is that, when the movable shutters 6 are moved from their open position, as shown in Fig. 3, to the position as shown in Fig. 2, the one leg of each shutter riding along the upper leg of the V-shape projection 15 will cause the opposite leg of each movable shutter to approach the adjacent leg of each cross bar, and finally contact therewith, to thus slightly wedge the shutters in their 55 closed position and prevent any lateral or loose movement.

As far as the specification has proceeded, 60 it will be understood that the V-shaped projection 15, the lug 16 and the lower leg 18 of the track 17, form a holding means for the one end of the cross bar, while a similar arrangement is provided on the opposite side piece so that the cross bars may be readily assembled and held in the frame. 65 Furthermore, the upper leg of each of the

V-shaped projections 15 form a track and support for the shutters as will be readily understood. Any number of cross bars and shutters may be provided for, depending on the height of the side pieces. 70

For simultaneously moving the shutters, the tie bars 7 are provided, as heretofore referred to; they having a bearing 19 formed in their lower ends through which passes the rod 8. 75

Referring for a moment to Fig. 2, it will be seen that the rectangular track 17 at the bottom of each side piece, has the base piece 20 formed integrally with the lower leg 18 and slightly curved, as at 21 for the reception of the pivotal dog 10. The handle 9 is provided at its one end with the slot 22 and the projecting pins 23 and 24, while the bar 8 is provided with the notch 25 as may be seen in Figs. 2, 3 and 4^a, so that the handle 9 may be operated either from a downwardly hanging position as shown in Fig. 4^a, or from an upright position, as shown in Fig. 3, it being simply necessary to engage either the pin 23 or 24 with the notch 25 to rotate the shaft 8 and force it upwardly and inwardly at approximately an angle of forty-five degrees to open the vents. In other words, move the shutters upwardly and inwardly to open the vents, or close the vents by moving the shutters downwardly and outwardly, in both instances, the dogs 10 travelling along the bases 20, as may be seen in Figs. 2 and 3. 90

The curvature of the bases as at 21, retains the dogs from escaping from the bases, which arrangement of the dogs also provides a locking means for the shutters in their open or closed positions. With the 100 ventilator formed in this manner, the shutters and cross bars may be quickly and easily assembled; the shutters may be easily and readily operated to open and close the vents formed by the cross bars, and the shutters may be easily locked in either position. Furthermore, the cooperating tracks, lugs and guides, support the cross bars and shutters and also provide guideways for the movable shutters, and by making one of the lugs at an angle to the other, as above referred to, the shutters when drawn to a closed position, have a slight wedging action, thus assisting in locking the shutters and providing against loose movement or rattle. 110

A slightly different arrangement of the shutters is shown in Figs. 6 to 10, the principle being the same, but the path of movement of the shutters being a horizontal one rather than a combined upward and inward movement. This is made possible by a slightly different arrangement of tracks 26 which may be understood by referring to Fig. 10 for the sake of clearness. Each track 125 comprises the angular way 27, the base 28, in 130

which is provided the depressions 29, and the slightly inclined end 30. A lug 31 is shown parallel to the portion of the track 27 so that a space is provided to receive one end 5 of one of the legs of the cross bar 32, this cross bar 32 being similar to the cross bar 13 in the other form.

Projecting downwardly from the center of the portion 28 of the track 26 is a 10 further guide 33 with a leg 34 at right angles thereto, to tightly hold the cross bar 32 in position, the portion 34 also forming a support for one leg of the movable shutter 35. This shutter 35 is similar to the shutter 15 6 with the exception that its ends are cut as shown in Fig. 8, the portions as at 39 and 40 being cut away, in each leg of the angle to leave the projections 41, which projections ride along the bases of the tracks 28 20 and rest in the depressions 29, that is, the center one and the one at the right hand side, or the center one and the one on the left hand side, depending upon whether the shutter is in its open or closed position. In 25 a like manner, these shutters 35 are moved by tie bars 42, and riveted near their ends are the straps 43, which in turn are riveted as at 44 to the shutter.

This form of ventilator is also quickly 30 and easily assembled. In operation, an inward movement of the bars 42 will cause the shutters to ride along the tracks from the position shown in Fig. 6 to the position shown in Fig. 7, to thereby open the vents, 35 while an outward pull of the bars will cause the movable shutters to travel outwardly and contact along their upper edge with one leg of the cross bars to thereby close the ventilator.

40 From the foregoing, it will be seen that the ventilator, whether constructed as shown in the one form or the other, comprises cross bars formed of angle iron and shutters formed of angle iron, which may 45 be easily purchased in the open market. Furthermore, the lug or guides, and projections may be so arranged that the shutters move away and towards the cross bars either in an inclined movement or in a 50 straight inward and outward movement to thereby open and close the vents as the occasion may require.

Furthermore, an arrangement is shown 55 for easily operating the shutters and for locking them in either of their two positions. In the several views, I have shown the ventilator as installed in a freight car without any special metal upper and lower rail, but it will be understood that these 60 portions might be used if it is ever desired.

The parts are relatively light in weight, 65 relatively cheap to purchase, and may be readily assembled. At the same time, I have provided a ventilator which will withstand the hard usage incident to railroad

installations, and prove highly effective in service.

Many slight changes might be made without in any way departing from the spirit and scope of the invention. 70

Having thus described my invention, what I claim as new and desire to secure by Letters Patent is:—

1. A ventilator comprising a frame, cross bars each formed of a plate bent in the 75 shape of an angle and the apex of each cross bar lying in a vertical plane, cooperating correspondingly formed slidable shutters arranged to move towards and away from the legs of the cooperating cross bars, 80 the movement of the shutters being in a plane extending across the frame of the ventilator and the movement of the shutters opening and closing the spaces between said 85 cross bars.

2. A ventilator comprising side pieces, angle irons arranged in an anticlinal manner and extending between said side pieces to form cross bars, cooperative correspondingly formed angle irons similarly positioned and located between said cross bars to form shutters and capable of an inward and outward movement and in a plane across the side pieces to thereby open and close the spaces between the cross bars. 95

3. A ventilator comprising side pieces, angle irons supported between said side pieces to form cross bars and to thus form vents, further cooperative slidably arranged angle irons located between said cross bars to form shutters and supported by said side pieces, and each of the said cross bars and the shutters so arranged that when the shutters are moved and the apex 100 of each shutter approaches the apex of the adjacent cross bar, the vents will be opened. 105

4. A ventilator comprising side pieces, lugs on said side pieces, angle irons extending between said side pieces forming cross bars and supported by said lugs said cross 110 bars forming vents, shutters formed of angles, tracks formed on said side pieces for supporting and guiding said shutters and means for moving the shutters inwardly to thereby open the vents, and outwardly to thereby close the same. 115

5. A ventilator comprising side pieces, lugs and tracks formed on said side pieces, cross bars having two legs supported by said lugs, said cross bars forming vents and shutters supported and guided by said tracks and said shutters adapted to slide in a plane toward and away from the legs of said cross bars to thereby open and close the vents. 120

6. A ventilator comprising side pieces, a plurality of projections formed on said side pieces, a plurality of cross bars in the form of angle irons, and the projections positioned on the said side pieces so as to support the angle irons with their apexes 125 130 135

in vertical alinement, a plurality of tracks also formed on the said side pieces, and a plurality of angular shutters arranged to be guided by said tracks and the said tracks so arranged that a downward movement of the shutters will cause the apexes thereof to approach to one leg of each cross bar.

7. A ventilator comprising side pieces, each of said side pieces having the projection 15, the lug 16 and the track 17 with the leg 18, angular cross bars supported between the track and the lug to form vents, shutters for said vents, each shutter supported and guided by its respective track and lug, and means for moving the shutters to thereby open and close the vents.

8. A ventilator as set forth in claim 7 with the additional means for locking the shutters in their open and closed positions.

20 9. A ventilator comprising side pieces, angular cross bars extending between said side pieces, angular shutters located between said cross bars, tie bars and the said shutters all secured to said tie bars, means 25 arranged to slide the shutters upwardly and inwardly across the side pieces to thereby open the vents between the cross bars, and means located near the ends of said tie bars for locking the shutters in their 30 open and closed position.

10. A ventilator comprising side pieces, lugs and tracks formed on said side pieces, angular plates supported by said plates and forming cross bars, other angular plates supported and guided by said tracks, forming shutters between said cross bars, joining means connected with said shutters and a bar mounted in said means, pivotal dogs on said bar, and means for rotating said bar 40 to thereby open and close the shutters.

11. A ventilator comprising side pieces, cross bars and a plurality of shutters located between said cross bars, tie bars connecting said shutters, a rod connected with 45 said tie bars, pivotal dogs mounted on the ends of said rod and arcuate tracks for supporting said dogs, and means for rotating the rod to thereby move the shutters to an open and closed position.

50 12. A ventilator comprising side pieces provided with lugs and angular tracks, cross bars supported by said lugs and tracks, movable shutters supported and guided in their movement along said tracks, the said 55 side pieces provided near their lower ends

with arcuate tracks, means for simultaneously operating all of said shutters, pivotal dogs forming a part of said means and said dogs travelling along said arcuate tracks.

13. A ventilator comprising side pieces, 60 lugs formed on said side pieces for supporting angular shaped cross bars, said cross bars forming vents, tracks formed on said side pieces and spaced from said lugs to support and guide a plurality of shutters 65 also formed of angular plates, the shutters and the cross bars so arranged that when the apexes of the shutters are in substantial alinement with the apexes of the cross bars the vents will be opened to their fullest extent.

14. A ventilator comprising side pieces, lugs and tracks formed on said side pieces, a plurality of cross bars supported by said lugs and said cross bars formed of right 75 angular shaped plates said cross bars forming vents, a plurality of similar shaped shutters supported by the tracks on said cross bars, the shutters closing the vents when at the forward edges of said cross bars, means for moving them within said cross bars to thereby open the vents, and means for locking them in such position.

15. A ventilator comprising side pieces, cross bars and shutters, the cross bars and shutters formed of right angular shaped plate arranged in anticlinal position, the cross bars forming the vents and the shutters positioned normally to occupy the space between the vents, means for sliding the shutters upwardly and inwardly across the side pieces and within the cross bars to thereby open said vents.

16. A ventilator comprising side pieces, 95 tracks formed on said side pieces, cross bars supported between said side pieces forming vents and shutters supported and guided in their movement by said tracks, the said shutters and said cross bars being formed of angular shaped plate, a leg of each shutter extending between the opposite legs of the cross bars when the shutters are in their closed position, means for sliding the shutters upwardly and inwardly within said cross bars to thereby open the vents and means for locking the shutters in their open and closed positions.

In testimony whereof I affix my signature.

WILLIAM E. WINE.
